UNITED STATES PATENT OFFICE.

JAKOB AUGUST HEDBERG, OF GOTENBORG, SWEDEN.

BLIND, ROLLER-BLIND, AND THE LIKE.

1,073,418.

Specification of Letters Patent. Patented Sept. 16, 1913.

Application filed February 27, 1912. Serial No. 680,186.

To all whom it may concern:

Be it known that I, JAKOB AUGUST HEDBERG, a subject of the King of Sweden, and resident of Odinplatsen 3, Gottenborg, in 5 the Kingdom of Sweden, have invented certain new and useful Improvements in Blinds, Roller-Blinds, and the Like, of which the following is a specification, reference being had therein to the accompanying 10 drawings.

This invention relates to improvements in blinds, roller-blinds and the like.

One characteristic feature of the said invention consists in an automatic locking device for the cord by means of which the blind is raised and lowered. The said locking device consists of two pivotally connected jaws, forming a pair of grippers. One of the said jaws is extended backward 15 and upward forming a lever, which is acted upon by the cord, bearing against the same, so that the jaws are forced one against the other and lock the cord. The rear end of the other jaw is pivoted to and, if necessary 20 25 slidably connected with the top lath of the blind.

A further characteristic feature of the invention consists of a self releasing adjusting device for the ribs of the blind, which 30 comprises a toothed segment, located above the top lath of the blind and in position to engage a pin or the like, projecting from the same. To the said segment an arm is pivoted, which, by holding the segment in a 35 raised position, permits the lath to return to its initial position. In self releasing adjusting devices of the said class hitherto used the arm, pivoted to the toothed segment, hangs freely down and, as the segment is 40 raised, the arm is placed with its lower free end upon a stationary support. This arrangement involves the disadvantage of the arm, for instance at a violent pull in the adjusting cord, being swung beyond the said 45 support instead of being placed on the same. For that reason the adjusting mechanism gets out of order and can be brought into the right position only with difficulty. According to this invention the said arm is 50 formed to a hook and the stationary support has such a position with relation to the hook, that the hook, during the movement of the toothed segment, slides on the support and at the end of the said movement falls 55 down and engages the support. The said

engagement, evidently, is more reliable than is the case, if the arm at its free end is placed on the support.

In the accompanying drawings Figure 1 is a front view of a blind arranged in accordance with this invention and provided with a roller for pulling up and lowering the blind. Fig. 2 is an end view of the same on a greater scale. Fig. 3 is a detail view of the device for fixing the end bearings 60 of the blind to the window-frame. Fig. 4 is a front view of a blind arranged in accordance with this invention and provided with two cords for the raising and lowering of the blind. Fig. 5 is an end view of 70 the locking device of the blind shown in Fig. 4. Figs. 6, 7 and 8 are detail views of the self releasing adjusting device of the blind. Fig. 9 is a longitudinal sectional view of the gripper jaws. 75

1, Figs. 1 and 2, is the window-frame, and 2, 2 are the end bearings of the blind, in which the roller 3 and the top lath are journaled. The said bearings 2, 2 are fixed to the window-frame in the manner described below. 80

5 is the operating cord of the blind wound around the roller 3, and 6 are the strings, wound around the roller 3, in opposite direction to the cord and passing through the 85 ribs 7 of the blind to the bottom rib in the ordinary manner.

8, 8 are the ordinary strings fixed to the edges of the ribs 7 and the top lath 4. The locking device for the operating cord 5 consists of two jaws 9 and 10, connected by a pivot 11 and forming a pair of grippers. Both the said jaws or at least the jaw 10 is 90 groove shaped, forming a guide for the cord 5, passing between the jaws. The jaw 9 of 95 the grippers is formed to an eye 12, slid on a loop 13 fixed to the lath 4, so that the grippers can swing around the said loop and be moved longitudinally of the same. The jaw 10 is extended backward and forms 100 a lever, which is acted upon by the cord passing through the grippers. In an arm 14, projecting from the jaw 9 a cord 15 is 105 fixed, by means of which the grippers can be swung around the loop 13 for the disengaging of the operating cord 5.

When the blind is raised, fully or partially, the part of the cord 5 located between the grippers and the roller 3 is strained and consequently the grippers occupy the posi- 110

tion shown in Fig. 2, in which the cord 5, acting upon the top part of the jaw 10, forces the said jaw against the jaw 9, so that the jaws 9, 10 engage the cord and prevent the same from sliding. If one now pulls the cord 15, the grippers are swung around the loop 13 and the pressure of the cord 5 on the top arm of the jaw 10 is reduced, so that the cord 5 can slide between the jaws 9, 10 and the blind can be raised or lowered. After the raising or lowering of the blind it is only necessary to leave hold of the cord 5. The grippers will then occupy the position shown in Fig. 2 and lock the cord.

In the locking device shown in Figs. 4 and 5 the grippers 9, 10 is pivoted to the lower side of the top lath and swingable longitudinally of the same. The jaw 9 has a pin 16, extending through a slot 17 provided in the jaw 10. The said pin is adapted to separate the two operating cords 5, 5¹, passing through loops 18, 18 and the grippers. When pulling the cords 5, 5¹ the grippers 9, 10 are swung backward and release the said cords. After the raising or lowering of the blind, one pulls the cord 15, fixed in the arm 14 of the jaw 9, and thus forces the grippers forward, so that it again engages the cords 5, 5¹ and locks the same.

For fixing the end bearings 2, 2 of the blind to the window-frame the following means are used: 19 is a preferably fork shaped mounting fixed to the window frame and provided at its lower end with a transverse pin 20, which is fixed in the shanks of the mounting. A bar or bolt 21, provided with a longitudinal slot 22, which extends substantially from the center of the bolt to its one end is slidably mounted on the said pin 20, embracing the pin with the said slot. The inner end 22^x of the slot 22 is enlarged or extended toward the one side of the bar for the purpose stated below. The horizontal, top part 23 of the end bearing 2 is provided with an opening 24, through which the bar 21 and the mounting 19 can be threaded. For the fixing of the end bearing 2 to the window-frame the bar 21 is brought into the position shown in Fig. 3. The part 23 of the end bearing 2 is then threaded on the bar 21 with its opening 24 and slid upward on the bar and the mounting to the position shown in Fig. 3 and the bar 21 swung upward into the position indicated by dotted lines in Fig. 2. The bar 21 is finally pushed inward to the position shown by full lines in Fig. 2, so that the part 22^x of the slot 22 engages the pin 20. In the said position the bar 21 supports the bearing. The bearing 2 and other parts of the blind keep the part 22^x of the slot 22 firmly in engagement with the pin 20, so that the bar is prevented in a reliable manner from being displaced accidentally. For the re-

moving of the bearing 2 one proceeds in reversed order, *i.e.* the bar 21 is pushed into the position, shown by dotted lines in Fig. 2, and then swung downward to the position, shown in Fig. 3 in which the bearing 2 slides downward on the same, acted upon by the weight of the blind. The bar 21 is provided, if necessary, with a hole 25 for the engaging of a suitable tool for the shifting of the bar 21.

The self releasing adjusting device shown in Figs. 6, 7 and 8 consists of the toothed segment 26, pivoted at 27 to the end bearing 2. In the top lath 4 of the blind a projection or pin 28 is provided, which, as the said top lath 4 is rotated, engages the teeth 26^x of the segment 26 in the usual manner and holds the blind in adjusted position. To the segment 26 is at 29 pivoted an arm 30, which in the position shown in Fig. 6 bears upon the top side of a pin 31, fixed in the end bearing 2. The free end of the arm 30 is formed to a hook. If the top lath 4 has been rotated to an oblique position with the pin 28 engaging one of the teeth 26^x of the segment 26 and the top lath is to be returned to its original position shown in Fig. 6, the lath is so rotated, that the pin 28 engages the nose 32 of the segment 26 and swings the segment 26 upward to the position shown in Fig. 7. During its movement to the said position the segment 26 moves the arm 30 toward the left, so that the hook shaped arm 30 falls down and engages the pin 31, Fig. 7. The arm 30 thus keeps the segment 26 in a reliable manner in its raised position with the teeth located out of the path of the pin 28, so that the lath 4 can return to its original position. During the last part of the return motion of the top lath 4 the pin 28 strikes the lower edge of the arm 30 and raises the arm out of engagement with the pin 31 and moves the same into the position shown in Fig. 6, the parts being thus returned to their initial positions.

Having now described my invention, what I claim as new and desire to secure by Letters Patent is:

1. In a locking device for blinds, roller-blinds and the like the combination of two pivotally connected jaws, between which the operating cord or cords pass, means pivotally connecting one of the said jaws with the top lath, and an extension of the other jaw, forming a lever arm acted upon by the said cord, substantially as described and shown in the drawings.
2. In a locking device for blinds, roller-blinds and the like the combination of two pivotally connected jaws, between which the operating cords pass, means pivotally connecting one of the said jaws with the top lath, an extension of the other jaw, forming a lever arm acted upon by the said cords, and a pin fixed in one of the jaws and ex-

tending through a slot in the other jaw, which pin separates the cords, substantially as described and shown in the drawings.

3. In a locking device for blinds, roller-blinds and the like the combination of two pivotally connected jaws, between which the operating cord or cords pass, means pivotally connecting one of the said jaws with the top lath, an extension of the other jaw, 10 forming a lever arm acted upon by the said cord, and means for connecting with the locking device a cord, by means of which the locking device can be swung into inoperative or operative position, substantially 15 as described and shown in the drawings.

4. In blinds of the class stated above the combination of a toothed segment, pivoted to one of the end bearings of the blind and coöperating with the top-lath, a hook shaped

arm which is pivoted to the said toothed segment and is normally carried by a stationary support, into engagement with which it is moved, as the toothed segment is raised during the releasing operation, and thus keeps the segment in raised position, 25 and a surface on the said arm acted upon by the top lath at the end of the releasing operation for bringing the hook-shaped arm out of engagement with the said stationary support, substantially as described and 30 shown in the drawings.

In witness whereof, I have hereunto signed my name in the presence of two subscribing witnesses.

JAKOB AUGUST HEDBERG.
